UNITED STATES PATENT OFFICE

149,962

DESIGN FOR A TEAPOT

Lea F. McCarty, Sierra Madre, Calif.

Application March 26, 1947, Serial No. 137,906

Term of patent 3½ years

(Cl. D44—25)

To all whom it may concern:

Be it known that I, Lea F. McCarty, a citizen of the United States and residing at 309 E. Sierra Madre Blvd., Sierra Madre, in the county of Los Angeles, State of California, have invented a new, original, and ornamental Design for a Teapot, of which the following is a specification, reference being had to the accompanying drawing, forming part thereof, in which:

Fig. 1 is a perspective view of a teapot showing my new design, and

Fig. 2 is a top plan view thereof.

I claim:

The ornamental design for a teapot, substantially as shown.

LEA F. McCARTY.
